T. DITSON.

MACHINE FOR BREAKING THE OUTER HUSKS OF THE COFFEE BERRY.

Thomas Ditsion
Machine for breaking or cracking in pieces, the outer husks of the
Coffe berry

The schedule referred to in these Letters Patent and making part of the same, containing a description in the words of the said Thomas Ditsion himself, of his improvement in a Machine for breaking or cracking in pieces, the outer husks of the Coffe berry.

To all persons, to whom these Presents shall come, Thomas Ditsion of Boston in the county of Suffolk & state of Massachusetts, etc, greeting.

Be it Known, that I the said Thomas Ditsion, have invented, made and applied to all, new and useful improvements of Machinery for the purpose of separating the external coats or husks of the Coffe berry, from the kernels or seed, which improvements, the principles thereof, and mode of use which I have contemplated the application of the same, together with the manner of using the same, I have herunto set forth and described in the following words and drawings, which, taken in connection form my specification—

On examination of the Coffe berry, we find it composed of three external coats or husks, forming two compartments surrounding the seeds. The object of the invention here described, is to crack or break open these husks when in a dry state, that by another process of winnowing they may be blown away or scattered from the seeds. The outer covering is a stouter and stronger texture than the second both being quite brittle and easily broken in pieces. The third, or covering immediately contiguous to the seed is of a more delicate nature than the others, and adheres more closely to the Coffe. The first operation of the machine here described is to crack or crush the outer husks, the second also tearing asunder the second covering, while the third and last operation is to rub off, or separate from the seeds, the covering immediately in contact with them.

The machinery for the first purpose, consists of a Cylinder A of wood or other suitable material, surrounded by an external covering B of sheet iron, perforated with holes by punches on the under surface

so that jagged edges are raised on the outer surface, similar to a common grater. The shaft of the cylinder A is revolved in proper boxes attached to the sides of the frame BB, which boxes admit of being moved laterally, so as to carry the cylinder farther from, or nearer to a concave surface D, covered with a sheet iron similar to the cylinder A - on the end of the shaft a of the cylinder A is fixed a cogged wheel, whose teeth enter into, and act upon the teeth of another cogged wheel on the shaft b. The last mentioned shaft b passes through a second wooden or iron cylinder O covered with stout wires inserted in leather of the same description used for carding wool -

D. concave surface D, covered like the cylinder O, passes a proper distance around the same, and with sufficient space between the jaws of the cards of each to effect the purpose of tearing off the second husk of the seed as it drops from the first Cylinder A and passes between the card surfaces -

The cogged wheel on the end of the shaft b is turned round by another cogged wheel on the extremity of another horizontal shaft c. The shaft c has a bevelled wheel d on its other end, the teeth of which enter into the teeth of a bevelled pinion e. on the top of the upright shaft f. The upright shaft f passes through the cone of frustum g. into which nails are thickly driven, so as to stand out from the concave surface about seven eights of an inch. Around the whole frustum, is another hollow frustum h of sheet iron, filled with holes similar to that are in the cylinder A. The rough edges of the iron thus raised by the punches together with the ends of the nails coming in contact with the seeds during the rotary motion of the cone of frustum, tear off the third and last covering, thus effectually separating the husks from the seeds and leaving the whole in a proper state for the next process of winnowing -

The broken husks and seeds as they leave from between the surfaces of the inner and outer cone frustum fall into a trough I placed underneath, from whence they are conveyed to a proper receptacle K on the outer extremity of the axis of the shaft c is fixed a flywheel L to regulate the motion of the machinery - The power

to set the machine in operation may be communicated to the shaft c by a crank on its end, or a pulley or pulleys operated on by a belt from a drum driven by steam, horses or water power, as is most convenient. There is also on the horizontal shaft c a set of small pulleys of three or more of different diameters, one to each of which a shifting belt may be placed; the belt from them passing over an opposite pulley of another, set on the end of a horizontal shaft c having a fluted roller or faced on it, at the mouth of the hopper E for the purpose of regulating the admission of the berries to the spaces between the cylinders and preventing them from clogging together, thereby stopping the feed of the machine.

Inclined planes L M serve to guide or convey the berries from each cylinder to the one below it, and the passage or course of the same from the hopper F to the receptacle K is clearly denoted by several arrows seen in the drawing.

I claim separating the seeds or kernels from the husks by the several operations and machinery hereinabove described in connection, and separately I claim the invention and use of a cylinder covered with sheet iron having holes punched in it, as hereinabove mentioned, for bruising or breaking in pieces the outer shell or covering of the coffee berry. Also the invention and use of a cylinder or framework of a cone, into whose outer surface nails are inserted of which is surrounded by an exterior casing of sheet iron, punched full of holes so that jagged edges shall be raised on the inner surface for the purpose of scratching or rubbing off the inner husk of the coffee berry.

In testimony that the above is a true specification of my invention, I have hereunto set my hand this twelfth Day of December in the year of our Lord Eighteen Hundred and Thirty four.
